UNITED STATES PATENT OFFICE.

SAUL BERNSTEIN, OF BALTIMORE, MARYLAND.

ARTIST'S SKETCHING OUTFIT.

SPECIFICATION forming part of Letters Patent No. 576,803, dated February 9, 1897.

Application filed August 4, 1896. Serial No. 601,666. (No model.)

To all whom it may concern:

Be it known that I, SAUL BERNSTEIN, a citizen of the United States, residing at Baltimore, in the State of Maryland, have invented certain new and useful Improvements in Artists' Sketching Outfits, of which the following is a specification.

This invention relates to an improved artist's outfit for outdoor sketching.

10 The object of the invention is to provide a serviceable and convenient apparatus which shall include an easel, a stand, a box to contain paper, colors, &c., an umbrella-holder, and a stool all constructed to coact together in use and so combined as to admit of being folded and packed together in small compass and carried by a suitable handle.

The invention is illustrated in the accompanying drawings, in which—

20 Figure 1 is a perspective of the outfit set up ready for sketching. Fig. 2 is a side view of the same outfit folded ready to be carried. Fig. 3 is an edge view of the folded apparatus. Fig. 4 shows four detail figures of the 25 stand and prop or support. Fig. 5 shows two longitudinal views of the easel-standard, the brace-bar at the bottom, and leg of the stool, also a cross-section view of same. Fig. 6 is a cross-section view, on a large scale, of the 30 standard and shows the top clamp for holding down the sketch-board. Fig. 7 is a detail view, partly in section, also on a large scale, of the standard shelf or ledge for supporting the sketch-board. Fig. 8 is a top view of said 35 shelf or ledge. Fig. 9 shows two views of one leg of the stool and the hinged foot on the leg.

Referring to the drawings, the letters A A' 40 designate the folding or pivoted legs of the stool, of which a is the canvas seat. The two inner legs A have at one side a board b, which serves as the bottom of a box, and the same legs at their lower end have a cross-bar c, to which a lid or half-cover d is secured by hinges d'. The other pair of legs A' at the top and 45 to the cross-bar e, to which the canvas seat is secured, has a half-cover B, secured by hinges e'. This last half-cover serves as a stand or table (see Fig. 1) when the apparatus is in use for sketching. When the stool is folded, 50 the two half-covers d B have their meeting edges at the center and form a complete lid for the box. (See Figs. 2 and 3.) The de-

scribed construction of the two half-lids, when the apparatus is set up for use, enables one lid B to take a horizontal position as a table substantially in a plane even with the canvas seat and enables the other to be tilted back, so that a projecting bar d², rigidly attached to it, may serve as a prop to support said table. (See Fig. 1.) When the two half-lids are closed, (see Fig. 2,) this projecting bar d² on one lid laps over onto the other lid.

The half lid or table B has on top a metal plate f, flush with the surface and through which a hole f' passes. A boss or thick block f² on the bottom of the table surrounds the said hole f'. The easel-standard C when set up passes through this hole, and thereby the said half-lid B serves as a stay for said standard, as well as for a table.

70 The projecting bar d² at the top end is beveled, as at g, and this beveled end enters a socket g' in the boss f². This bar also has near the end a hole h, and a spring-bolt h', movable in a keeper or slideway h², attached to the bottom of the table, enters said hole h in the bar and thereby locks the bar when its beveled end is in the socket g' and keeps it from disconnecting. This device by keeping the table fastened up insures that the 80 standard C will not lose its upper stay. While the prop-bar d² is in the position shown in Fig. 1 to support the half-lid B as a table, the half-lid d serves as an inclined holder to support papers or sheets of drawing whose 85 ends are resting in the box.

The lower cross-bar c on the legs A has on its under side a metal plate c', and the lower end of the standard C has a racked bar D, secured to it by a hinge i. When the outfit 90 is set up in the field, as in Fig. 1, the teeth of the racked bar engage the metal plate c', (see also Fig. 5,) and thereby the foot of the standard is held immovable. The extremity of the standard has a prong i', which enters 95 the ground and also serves to hold the standard. The two stool-legs A, which have the metal plate c', also have at their ends hinged feet b'. When in use, these feet spread out on the surface of the ground and prevent the end 100 of the legs from penetrating the ground, but when not in use these hinged feet may be turned back and take position alongside of the leg, as indicated by broken lines in Fig. 9.

A sliding wedge E has a dovetailed groove j , and the standard C has a longitudinal plate j' with beveled edges on which the said groove of the wedge fits. The wedge may slide up 5 or down on the standard. When the outfit is set up, this wedge enters the hole j' in the table B and serves to tighten the standard, which is also in said hole. The standard C is made in short lengths or sections, which 10 are united by a screw-joint K. (Seen in section in Fig 5.)

The shelf or ledge F for supporting the sketch-board is shown in Figs. 1, 7, and 8. This shelf has two parallel longitudinal edge 15 flanges k , and at the center has a hole m , through which a spring-catch n passes. This spring-catch is secured at the bottom side of the shelf by a rivet n' , and it passes up through the said hole m , and then projects laterally 20 at the front over one of the flanges k and terminates in a thumb-piece n^2 . The shelf sets on an arm or stud G, which projects horizontally from the standard C. On its top 25 side this arm has a notch o , which receives the elbow part of the spring-catch n . (See Fig. 7.) The bottom of the shelf F has two parallel cross-bars p , one of which is shown in Fig. 7, and both are indicated by broken lines in Fig. 8. These two cross-bars p take 30 on opposite sides of the said stud G and by contact with said stud serve to steady the shelf. When the spring-catch is engaged with the notch o , the shelf will be retained 35 in position. To detach the shelf, it is only necessary to lift the projecting end n^2 of the catch.

The arm or stud G, which supports the shelf, is vertically adjustable on the standard C. This is effected by the side grooves q in the 40 standard and a slide-head I, movable up and down by plates q' , fitting in said grooves. The slide-head I carries the arm or stud G and has a set-screw r , which serves to hold it to the standard at any height to which it may 45 be set.

A top clamp J is employed on the standard to hold down the sketch-board v . (Shown in Fig. 3.) The sketch-board will set on the shelf F, and this top clamp J will engage the 50 upper edge of the sketch-board and keep it pressed down to its seat on the shelf. The same grooves q before referred to receive plates q^2 on the top clamp and thus form a slide-head. A set-screw s on the clamp impinges against the standard C, and thus confines the slide-head and clamp in position. The slide-head carries a clamp-blade t , whose 55 prongs t' point downward. This blade has two parallel projecting arms u , which loosely fit in holes or sockets in the slide-head and may be pushed in or drawn out a little. The set-screw passes through the clamp-blade t . It will now be seen that the prongs t' of the 60 top clamp-blade may be entered into the upper edge of the sketch-board or stretcher which may happen to be in position on the shelf F.

The top extremity of the standard has an upright bolt w , on which is fitted an umbrella-holder. This holder comprises a collar w' , 70 surrounding the bolt, and a suitable clamp device w^2 , swiveled to the collar. The said clamp grasps the handle x of the umbrella. In this class of clamps a set-screw is usually employed to tighten the clamp on the umbrella-handle. Such clamps afford a wide 75 range of movement of the umbrella-handle, and thereby enable the umbrella to be adjusted to any desired position, so as to afford shade for the person occupying the stool-seat. 80 When there is but little breeze, the easel-standard C may thus be utilized to hold the umbrella, but of course if the wind should blow too hard the umbrella thus supported would make the easel too unsteady for the 85 artist's work, and in such case the umbrella would have to be removed.

When the entire outfit is folded (excepting only the standard) ready to be carried, a hook l , pivoted on the prop-bar d^2 , engages 90 with a staple or eye l' , which projects through the cover B and also through a slot l^2 in said prop-bar. This staple or eye l' is rigidly fixed to the bottom board b or to a cross-piece in the box, of which said board b is the bottom. 95 When the parts are thus folded, a handle y is employed and a cord z . The cord is passed twice around the folded parts (see Figs. 2 and 3) and over the base ends y' of the handle and the end secured firmly, and said cords bind 100 all the folded parts.

Having thus described my invention, what I claim is—

1. In an artist's sketching outfit, the combination of a stool having a canvas seat and crossed pivoted legs, one pair of which has a bottom board, b , and ends forming a box, and a hinged half-cover, d , provided with an attached prop-bar, d^2 ; and the other pair of legs has at the top a hinged half-cover, B, 110 said two half-covers, when the stool is folded, having their meeting edges at the center, and when the stool is set up for use said hinged half-cover, B, may take a horizontal position 115 as a table substantially in a plane even with the canvas seat, and be sustained by said prop-bar attached to the other half-cover.

2. In an artist's sketching outfit, the combination of a stool having a canvas seat and crossed pivoted legs; a table, B, hinged to the 120 said stool substantially in a horizontal plane even with the seat, and said table provided with a hole; an easel-standard, C, which, when set up, passes through said hole in the table, whereby the hinged table serves as a stay for 125 said standard.

3. In an artist's sketching outfit, the combination of a stool having a canvas seat and crossed pivoted legs; a table, B, hinged to the 130 said stool substantially in a horizontal plane even with the seat, and said table provided on the bottom with a boss, said boss having a socket, g' ; a prop-bar, d^2 , connected with the stool-legs and its upper end having a hole,

h, and the extremity of said end adapted to enter said socket; and a spring-bolt, *h'*, on the bottom of said table which enters the hole in the prop-bar and thereby locks the latter 5 while its extremity is in the socket.

4. In an artist's sketching outfit, the combination of a stool having a canvas seat and crossed pivoted legs; a lower cross-bar on one pair of legs having a metal plate, *c'*; a table, *B*, 10 hinged to the said stool substantially in a horizontal plane even with the seat and said table provided with a hole; an easel-standard, *C*, which, when set up, passes through said hole in the table; and a racked bar, *D*, secured to 15 the lower end of said standard and adapted to engage the said metal plate, as set forth.

5. In an artist's sketching outfit, the combination of a stool having a canvas seat and crossed pivoted legs; a table, *B*, hinged to the 20 said stool substantially in a horizontal plane even with the seat, and said table provided with a hole; an easel-standard, *C*, which when set up, passes through said hole in the table;

and a wedge, *E*, secured to said easel-standard by a dovetailed slide device so as to be 25 movable up and down—said wedge entering the hole in the table through which the easel-standard passes.

6. The combination of an easel-standard having side grooves, *q*; a slide-head, *I*, having plates which take in said grooves and is vertically movable on said standard, and held in position by a set-screw, *r*; an arm or stud, *G*, projecting from said slide-head and having a notch; a shelf or ledge, *F*, adapted to set 30 35 upon the said arm or stud and provided with a spring-catch, *n*, having an elbow-bend which engages said notch and thereby retains the shelf in position.

In testimony whereof I affix my signature 40 in the presence of two witnesses.

SAUL BERNSTEIN.
